UNITED STATES PATENT OFFICE.

GEORGE H. PIERCE, OF NEEDHAM, MASSACHUSETTS.

LATCH.

SPECIFICATION forming part of Letters Patent No. 702,074, dated June 10, 1902.

Application filed September 11, 1901. Serial No. 75,099. (No model.)

To all whom it may concern:

Be it known that I, GEORGE H. PIERCE, a citizen of the United States, residing at Needham, in the county of Norfolk and State of Massachusetts, have invented certain new and useful Improvements in Door-Latches; and I do hereby declare the following to be a full, clear, and exact description of the invention, such as will enable others skilled in the art to which it appertains to make and use the same.

This invention relates to door-latches; and it consists in the novel construction and combination of the parts hereinafter fully described and claimed.

In the drawings, Figure 1 is a front view of the latch. Fig. 2 is a rear view of the latch with the back plate removed. Fig. 3 is a cross-section taken on the line $x-x$ in Fig. 1. Fig. 4 is a longitudinal section taken on the line $y-y$ in Fig. 2. Fig. 5 is a side view of the key.

A is the frame of the latch, which is provided with a front plate a.

B is the back plate, which is let into the frame A.

C is the bolt, which slides in longitudinal guides c in the frame A. The frame A is also provided with a partition-plate d, arranged parallel with the plate a, and D is a chamber between the said plates a and d in the front part of the frame.

E is a spring which normally presses the bolt C forward.

The bolt C has a tooth or rib c' on its side next to the front plate, and F is a tumbler which is pivoted on a pin f, projecting from the plate a under the chamber D. The tumbler F is pressed upward into engagement with the tooth c' by means of a spring G, and g is a stop on the plate a, which limits the upward movement of the tumbler.

H is a vertical pin for holding the tumbler F out of engagement with the tooth c'. This pin is slideable and revoluble in the frame A, and h is a catch on the frame A. The pin H has a projection h', which is slipped into engagement with the catch h when the pin is depressed; but any other approved means may be used for holding the tumbler out of action. When the tumbler is held out of ac-

tion, the bolt may be operated as an ordinary spring latch-bolt.

The plates a and d are provided with keyholes j and j', arranged in line with each other and formed to fit the key J. The key J has a slot k, which engages with the plate d, so that the part k' of the key operates the bolt C and the part m works in the chamber D and operates the tumbler. The key may be provided with any desired grooves for engaging with wards or guides on the plates a and d in any approved manner.

N is a raised escutcheon on the plate a. This escutcheon is provided with a keyhole n, which is different in form from the keyholes j and j' and which is arranged out of line with them.

P is a pin which projects from the back plate B on the axis of the three keyholes. The key is first inserted through the keyhole n and is then partially revolved on the pin P and is pushed through the keyholes j and j'. The outer keyhole n affords no clue to the form or size of the inner keyholes j and j', and the escutcheon conceals the inner keyholes and prevents the insertion of instruments for picking the latch or for ascertaining the actual position, size, and form of the inner keyholes and their adjuncts. The latch can only be operated by the key pertaining to it when the tumbler is in operation, and when such key is inserted the part k' shoots back the bolt at the same time as the part m depresses the tumbler and permits the said bolt to be retracted.

What I claim is—

In a latch, the combination, with a frame provided with a stationary front plate having an inner keyhole, of an escutcheon on the said front plate having a stationary plate provided with an outer keyhole which is arranged out of line with the aforesaid inner keyhole, and a projecting guide-pin for the key arranged on the axis of the two said keyholes, substantially as set forth.

In testimony whereof I affix my signature in presence of two witnesses.

GEORGE H. PIERCE.

Witnesses:
